DAVID FRISHMAN, OF NEW YORK, N. Y.

DESIGN FOR A CIGAR AND ASH HOLDER.

56,745.

Specification for Design.

Patented Dec. 14, 1920.

Application filed February 3, 1920. Serial No. 355,979. Term of patent 7 years.

To all whom it may concern:

Be it known that I, DAVID FRISHMAN, a citizen of the United States and residing at New York, New York county, and New York State, have invented a new, original, and ornamental Design for a Cigar and Ash Holder, of which the following is a specification, reference being had to the accompanying drawing, forming a part thereof, and in which—

Fig. 2 is a bottom plan view of the same.

Fig. 3 is a front view of the design.

What I claim as new, is:

The ornamental design for a cigar and ash holder, as shown.

In testimony whereof, I have signed my name to this specification in the presence of two subscribing witnesses, this the 26th day of January, 1920.

DAVID FRISHMAN.

Witnesses:

A. W. BAKER,
JAMES F. DUHAMEL.
